United States Patent Office

Des. 198,979
Patented Aug. 25, 1964

198,979

SPADE OR SIMILAR ARTICLE

George Petoe, 23359 W. Roosevelt Road,
South Bend, Ind.

Filed Dec. 13, 1962, Ser. No. 72,919

Term of patent 14 years

(Cl. D39—1)

FIG. 1

FIG. 2

FIG. 5

FIG. 3

I claim:

The ornamental design for a spade or similar article, substantially as shown.
